(57) **CLAIM**

The ornamental design for a bi-fold wallet with pull tabs, as shown and described.

DESCRIPTION

FIG. 1 is an isometric view of the bi-fold wallet with pull tabs in a partially open configuration embodying the present ornamental design;

FIG. 2 is front view thereof in a closed configuration;

FIG. 3 is a rear view thereof in a closed configuration;

FIG. 4 is front view thereof in an open configuration with the pull-tabs stowed;

FIG. 5 is front view thereof in an open configuration with the right pull-tab deployed;

FIG. 6 is a rear view thereof in an open configuration; and, FIG. 7 is a top down view thereof in a closed configuration; and,

FIG. 8 is a bottom up view thereof in a closed configuration. The dashed lines in FIGS. 1, 4, and 5 illustrate the contents of the storage compartments and form no part of the claimed design. The broken lines around the perimeter of the wallet in FIGS. 1-7 represent stitching, and are incorporated as part of the claimed design.
